UNITED STATES PATENT OFFICE.

HARRY C. WATSON, OF LANCASTER, OHIO.

PULP-BEATER.

1,184,058.

Specification of Letters Patent. Patented May 23, 1916.

Application filed July 2, 1915. Serial No. 37,723.

To all whom it may concern:

Be it known that I, HARRY C. WATSON, a citizen of the United States, residing at Lancaster, in the county of Fairfield and State 5 of Ohio, have invented certain new and useful Improvements in Pulp-Beaters, of which the following is a specification.

My present invention relates to pulp beaters and has for its main object the provision 10 of an improved structure, constituting the abutting surface between which the pulp is passed and ground to dry out its fibers and reduce it to the finely divided state necessary for its successive working.

15 A further object of my invention resides in so constructing and so arranging this structure of abutting surfaces or filling as they are commonly known, that they are easily renewable and repairable, the fillings 20 of both the cone and shell being so constructed that one or both of them may be removed from its applied position with comparative ease. This arrangement enables me to renew the heavy working parts of 25 the machine after once these parts have become worn out.

These objects I accomplish by the structure shown in the accompanying sheets of drawings, in which similar characters of reference designate corresponding parts, and in which:

Figure 1 is a view in central section of the shell of a conventional type of pulp beater. Fig. 2 is a face view of the structure shown 35 in Fig. 1, Figs. 3 and 4 are top plan and side views respectively of one of the shell filling sections, Fig. 5 is an end view looking from the left of the structure shown in Fig. 3, Fig. 6 is a central vertical section of a 40 cone adapted to coöperate with the shell shown in Fig. 1, Fig. 7 is an end view looking from the left of the structure shown in Fig. 6, Figs. 8 and 9 are top plan and side 45 elevational views respectively of one of the filling sections applied to the cone shown in Fig. 6, and, Fig. 10 is a central vertical section of the cone and shell shown in their co-operative relation.

Referring to the drawings, the shell is des- 50 ignated by the reference numeral 1, this shell being provided with an inlet portion 2 and a cap 3 covering its outer open end, this cap being further provided with an outlet portion 4. The inner end of the cone is pro- 55 vided with an annular shoulder 5 forming a groove 6 into which the beveled end of the

inner end of the filling sections 7 are adapt- 60 ed to fit. It will be noted that these filling sections are provided in suitable numbers and so shaped that they exactly fit the inner 65 surface of the shell, the outer surfaces of these sections being smooth to fit the smooth inner surface. The outer ends of the cone sections are somewhat larger than the inner ends and are provided with cut-out por- 70 tions such as shown at 8, these cut-out por- 75 tions forming an annular groove when in assembled relation to accommodate the ring shown at 9. This ring is preferably of a somewhat resilient nature and is split as 80 shown at 10, the ring in this manner being capable of a slight expansive action to effec- 85 tively hold the filling sections in place when the cap 3 is removed from its opera- 90 tive position, as, for instance, when it is de- 95 sired to inspect the interior of the beater as a whole, or to renew or replace the cone. Reference to Fig. 10 will show that the cap 3 will itself hold the shell sections in place when the entire machine is in its complete 100 working order. These sections are all made of the desired metal and are provided on their inner surfaces with inwardly extending ribs 11, these ribs being arranged to ex- 105 tend obliquely to the axis of the machine 110 and are further provided in such spaced re- lation as to present spaces 12 between them, into which the pulp may pass.

The cone itself is designated as a whole by the numeral 13, this cone being provided 90 with a bore 14 at its inner end upon which the shaft 15 is mounted and is further pro- 95 vided with a spider arrangement 16 at its outer end, into which the shaft 15 also fits as is shown more particularly in Fig. 10. 100 The inner end of this cone is formed with an annular shoulder 17, this shoulder be- 105 ing so grooved to present angular passageways 18 to coöperate with the spaces formed by the ribs on the fillings in order to permit the free passage of the pulp. The shoulder 17 forms an annular groove 19 into which the inner end of each of the cone filling sections 20 securely fit, the outer edge of this cone being also provided with an annular 105 shoulder 21 to serve as an abutment for the outer ends of each of the filling sections. Each filling section is further provided with a number of countersunk bolt holes 22 through 110 which the bolts 23 may pass to accommodate the nuts 24 on their outer ends and located within the hollow cone 13. In this manner,

the filling sections are all rigidly held in position and it will be further noted that each of these filling sections is provided with a similar arrangement of outstanding ribs 25, these ribs coöperating with the ribs on the shell filling to serve the purpose of disintegrating the fibers of the pulp.

From the foregoing, it will be apparent that I have provided a type of beater where-
15 in both the shell and cone fillings may be removed and replaced whenever desired. It is customary to wear these fillings down until their ribs are substantially flush with the body, at which time it is, of course, necessary to remove them and replace them. The cone may be removed by removing the cap 31, and this removal will not cause the collapse of the fillings within the shell, inasmuch as the ring 9 is in such position as to
20 permanently hold them in place. Further, this ring is made split in order that the workmanship of the annular grooves 8 need not be absolutely perfect. In this connection, the expansive nature of the ring is also
25 desirable, since it may be contracted or expanded to suit conditions.

What I claim, is:

1. In a pulp beater, a conical shell to

which pulp is adapted to be fed and withdrawn, a cone fitting within said shell and 30 adapted to be rotated therein, an annular shoulder on the inner end of said cone, an outstanding shoulder on the outer end of said cone, a plurality of suitably shaped filling sections fitting in the space between 35 said shoulders and each provided with bolt holes, bolts for attaching said sections to said cone, and a plurality of outstanding ribs on each of said sections.

2. In a pulp beater, a conical shell to 40 which pulp is adapted to be fed and withdrawn, a shoulder on the inner end of said shell, a plurality of suitably shaped filling sections arranged to fit the inner surface of said shell, said sections being provided with a cut-out portion in their outer ends 45 to form an annular groove, a ring adapted to fit in said groove to hold said sections in place, and a suitable cone within said shell adapted to be rotated therein.

In testimony whereof I affix my signature in presence of two witnesses.

HARRY C. WATSON.
